WALTER WILLIAM HALES, OF NEW YORK, AND ARTHUR HINE, OF CEDARHURST, NEW YORK; SAID HINE ASSIGNOR TO SAID HALES.

PROCESS AND APPARATUS FOR IMPROVING COMBUSTION IN EXPLOSIVE-ENGINES.

1,391,630.

Specification of Letters Patent. Patented Sept. 20, 1921.

Application filed March 26, 1920. Serial No. 369,148.

To all whom it may concern:

Be it known that we, WALTER W. HALES and ARTHUR HINE, both citizens of the United States, and residents, respectively, 5 of the city of New York, borough of Manhattan, in the county and State of New York, and of Cedarhurst, in the county of Nassau and State of New York, have invented a new and Improved Process and 10 Apparatus for Improving Combustion in Explosive-Engines, of which the following is a full, clear, and exact description.

This invention relates to means for improving the combustion of fuel in explosive 15 engines of all kinds, and has reference more particularly to a process and apparatus for the purpose indicated, which consists in introducing ozonized air, ozonized oxygen, or ozone into the cylinders of an explosive engine along with the vaporized fuel mixture.

It is a well-known fact that the exhaust 20 gases issuing from internal combustion or explosive engines carries a high percentage of carbon monoxid often amounting to as much as fifteen to twenty-five per cent. This carbon monoxid indicates that the fuel is incompletely burned, and therefore, a large amount of heat which should be used, is wasted. The combustion can be somewhat 25 improved by increasing the percentage of air in the explosive mixture introduced into the cylinders of the engine, but it has been found that beyond certain limits it is impracticable to introduce a higher percentage 30 of air. When carbon burns with incomplete combustion so that carbon monoxid is formed, the following reaction takes place:

35 When carbon monoxid burns with sufficient oxygen present, carbon dioxid is formed according to the following reaction:

40 Thus it is seen that the larger precentage of heat in the combustion of carbon is generated by the combustion of carbon monoxid to carbon dioxid.

An object of this invention, therefore, is 45 to utilize the large quantity of heat represented by the carbon monoxid in the exhaust gases of an internal combustion engine, by introducing ozonized air, ozonized oxygen, or ozone along with the explosive mixture

of fuel since ozone is a much more active 55 oxidizing agent than atmospheric oxygen, and therefore, all the carbon monoxid will be completely burned to carbon dioxid, with a resulting increased efficiency of the engine. The introduction of ozone into the cylinders of an explosive or internal combustion engine will also prevent the formation of elementary carbon on the walls of the cylinders, the piston, and the spark 60 plugs, so that the engine will continue to operate efficiently through long periods of time without necessitating cleaning the spark plugs or regrinding the valves of said engine. The elementary carbon in said cylinders and on said spark plugs and valves 65 may also be removed by passing ozone, ozonized air, or ozonized oxygen into said cylinders along with the vaporized fuel.

While any suitable apparatus may be used 70 for accomplishing the above result, we have invented an apparatus which is disclosed in the accompanying drawing, in which the figure is a side elevation of the apparatus.

Referring to the accompanying drawings 75 by numerals, 10 indicates any explosive or internal combustion engine provided with cylinders 11, and a vaporized fuel intake manifold 12, through which the vaporized fuel is admitted to the cylinders. A carbureter 13 is provided on said manifold 12, which vaporizes the fuel and mixes it with air as it enters said manifold, and the explosive mixture is drawn into the cylinders on the suction stroke of the pistons. The 80 engine 10 includes a fly wheel 14 mounted on a crank shaft 15, and any standard alternating current generator 16 may be secured to said crank shaft so as to generate an alternating current of electricity as said engine 85 operates. The current of electricity is delivered to any standard transformer 17, by means of an electrical circuit 18, and said transformer steps up the voltage of said current and delivers it through an electrical 90 circuit 19 to any standard ozone machine 20. This ozone machine is connected by a pipe 21, to the manifold 12, and said pipe includes a valve or cock 22. The pressure inside the manifold 12 is below atmospheric 95 pressure so that air is drawn into an intake pipe 23 on the ozone machine, through said ozone machine, through the pipe 22 and into said manifold. The flow of the ozonized air 100

into said manifold is controlled by means of the valve 22. Instead of passing air through said ozone machine, pure oxygen may be introduced into the intake pipe 23 from any oxygen container or other source of oxygen supply. We may also supply ozone to said manifold 12 from any source other than the apparatus shown.

We would state in conclusion that while 10 the illustrated example constitutes a practical embodiment of our invention, we do not limit ourselves strictly to the mechanical details herein illustrated, since manifestly the same may be considerably varied without departure from the spirit of the invention as defined in the appended claim.

What is claimed as new is:

In a device of the class described, an explosive engine provided with an intake manifold, a pipe connected to said manifold, 20 means for introducing vaporized fuel and air into said manifold, an ozone machine connected to said pipe, an alternating current generator operated by said engine, a transformer means connecting said generator to said transformer for supplying an alternating current thereto, and connecting means between said transformer and said ozone machine for supplying a high voltage alternating current to said ozone machine.

WALTER WILLIAM HALES.
ARTHUR HINE.
